UNITED STATES PATENT OFFICE.

SAMUEL L. HANSON, OF ALBERT LEA, MINNESOTA.

ADJUSTABLE CATTLE STALL.

Application filed January 6, 1926. Serial No. 79,649.

This invention relates to cattle stalls and particularly to an adjustable connecting means for the partition members and stanchion frames used in such stalls, it being understood that the connecting means might be used for connecting any suitable spaced posts. Cattle stanchions having supporting frames are now commonly used and are made up and assembled in a factory all ready for installation in the barn where they are suitably spaced and fixed in position. The partition members divide the stalls, one from the other, and are usually anchored at their rear ends and have a horizontally extending portion at their forward ends which is connected to the stanchion frames. The spacing of the stanchion frames for determining the width of the stall varies, and it is desirable to have an adjustable connection between the posts forming the sides of the adjacent stanchion frames and the partition members so that the proper adjustment can be made when the frames are installed. It is also desirable to have a simple, efficient and quite rigid connecting means for said frames and partition members.

It is an object of this invention, therefore, to provide a simple, efficient and rigid connecting means for the partition members and adjacent stanchion frames or posts, which connecting means may be adjusted to vary the spacing of said frames or posts.

It is a further object of the invention to provide a connecting means for two spaced stanchion frames comprising arms secured to one end to the sides of said frames and extending between the same, said arms being offset to extend in parallel relation, members being provided adjustably secured to said arms and also secured to a partition member disposed between said frames.

It is also an object of the invention to provide such a device as set forth in the preceding paragraph in which the said connecting members are reversible so that the stanchion frames or posts may be closely spaced or spaced a much greater distance and a very rigid structure maintained.

These and other objects and advantages of the invention will be fully set forth in the following description made in connection with the accompanying drawing in which like reference characters refer to the same parts throughout the different views and in which:

Fig. 1 is a horizontal section through ad-

jacent posts of cattle stanchions embodying the present invention, some of the parts being broken away and other parts shown in horizontal section, said section being taken substantially on the line 1—1 of Fig. 2, as indicated by the arrows;

Fig. 2 is a vertical section taken on the line 2—2 of Fig. 1, as indicated by the arrows; and

Fig. 3 is a vertical section taken on the line 3—3 of Fig. 2, as indicated by the arrows.

Referring to the drawings, a pair of spaced vertically extending posts 5 are shown. While these posts may be used in various structures and may be of various shapes, in the embodiment of the invention illustrated they are shown as made of substantially cylindrical pipe and as comprising the sides or posts of adjacent frames of cattle stanchions. The stalls using such cattle stanchions are commonly divided by a partition member 6, the horizontal portion of which is shown in Fig. 1. The member 6 is also illustrated as made of round pipe and this member divides the stalls and usually extends rearwardly and downwardly to the floor. For connecting the members 5 and 6, connecting members 7 are used, similar in construction, which members have head portions 7^a formed to partially embrace the pipes 5 to which are connected complementary clamping portions 8, portions 7 and 8 being connected by headed and nutted bolts 9, said bolts being illustrated as of well-known carriage type having square or angular shaped portions adjacent their heads to prevent turning thereof. The members 7 extend towards each other and said members are formed with an angle so that their outer ends are offset, said outer end portions or arms 7^b extending in spaced parallel relation.

As shown in Figs. 1 and 3, the arms 7^b are hollow or of box section, this having parallel sides and said members having elongated slots 7^c extending through their opposite sides. A pair of connecting plates 10 is provided which members are similar in construction and have flanges 10^a fitting against the sides of the arms 7^b and apertured to receive the headed and nutted bolts 11 which also extend from the arms 7^b and through the slots 7^c thereof, said bolts also being shown as of the carriage type having square or angular shaped parts 11^a adjacent their heads, disposed in the slots 7^c to

prevent turning thereof. It will be seen that the bolts 11 can slide lengthwise of slots 7^a so that members 10 can be secured in various positions along the arms 7^b. The members 10 have semi-cylindrical portions 10^b having their axes extending substantially at right angles to the flanges 10^a which portions 10^b are adapted to substantially embrace one side of the partition member 6, members 10 having bosses 10^c adapted to receive the headed and nutted bolts 12 which connect the members 10 and clamp the same onto member 6. The bolts 12 are also shown as of the carriage type having square portions 12^a preventing rotation thereof.

In operation the member 7 can quickly be attached to the post 5 by applying the heads 7^a and 8 thereto and tightening the bolts 9. The members 7 and 8 will be set at the proper height for the front end of the partition member 6 as shown in Figs. 1 and 2, and the members 10 secured to the member 6. The post 5 can now be spaced as desired with the bolts 11 loose. If the posts are spaced a considerable distance apart, the members 7 will be disposed as shown in full lines in Figs. 1 and 2. In said figures the bolts 11 are shown as disposed substantially at the longitudinal center of the slots 7^a and said bolts can be moved to the end of said slots so that the post 5 could be spaced still further apart. It will be noted that the flanges 10^a extend well to one side of the portions 10^b. Flange 10^a always has a wide bearing surface on the arms 7^b and a very rigid construction is provided. With the members 7 disposed as shown in Figs. 1 and 2 the posts 5 could be set closer together, the posts being moved together until the outer edge of the flange 10^a engages the inclined portion of member 7, connecting arms 7^b to the head 7^a. In order, however, to be able to space the posts 5 still closer together, the members 7 are made symmetrical about their horizontal central plane so as to be reversible. When it is desired, therefore, to space the posts 5 closer together the members 7 will be reversed and member 7 shown in Fig. 1 in full lines as connected to the post 5 at the left hand side of said figure will be turned as shown in the dotted lines, so as to embrace post 5 at the right hand side of Fig. 1 and the members 7 at the right will be reversed from the full line position shown to the dotted line position so as to embrace the post at the left hand side of Fig. 1. When the members 7 are reversed and disposed in the position shown in dotted lines in Fig. 1, it will be seen that the posts 5 can then be moved much closer together. The portions 10^b of members 10 are then adjacent the inclined portions of members 7 which connect heads 7^a and arms 7^b so that the posts 5 can thus be brought quite close together. Attention is also called to the fact that the flanges 10^a still have a wide bearing

on the arms 7^b so that a very rigid structure is provided. By having the members 7 arranged to be reversed, a more rigid structure is obtained in both positions than if the arms 7^b were merely made longer and the flanges 10^a made shorter to get the adjustment. The partition member 6 may, of course, be adjusted longitudinally as desired in the portions 10^b, it being noted that the arms 7^b extend above the member 6. 75 75

From the above description it is seen that applicant has provided a very simple and efficient connecting means for adjacent frames or posts such as used in cattle stanchions and by means of which the posts can easily and quickly be secured in different spaced positions. The parts required are very few and quite simple. It will be noted that the members 10 are similar, as are also the members 7 and the members 8. These various members can therefore be used interchangeably and it is not necessary to match a particular member 8 with a particular member 7, or to match mating portions of the members 10. The required parts are thus few in number and when assembled, a very flexible construction is provided and yet one that is extremely rigid when in operative position. It will, of course, be understood that various changes may be made in the form, details, arrangement and proportions of the parts, without departing from the scope of the applicant's invention, which generally stated consists in a device capable of carrying out the objects above set forth in the novel parts and combination of parts disclosed and defined in the appended claims. 95 95

What is claimed is:

1. A device of the class described, having in combination spaced posts, connecting members for said posts, each having a head portion adapted to engage and be secured to one of said posts and having an offset arm projecting from said head portion, said arms being adapted to extend towards each other in parallel relation, a horizontally extending member, and a connecting means movable longitudinally of and adapted to be secured on said arms and secured to said last mentioned member. 105 110 115

2. A device of the class described having in combination spaced stanchion frames, connecting members for said frames each having a head portion adapted to engage and be secured to one of said frames and also having an offset arm projecting from said head portion, said arms being adapted to be disposed in parallel relation, a partition member disposed between said frames and extending at right angles thereto, partition connecting members having laterally offset flanges and having portions embracing said partition member, means for securing said partition connecting members to said partition member, said flanges being 120 125 130

slidable on said arms and means for connecting said flanges to said arms and holding said flanges in various positions thereon, said first mentioned connecting members being reversible whereby said frames may be spaced quite close together.

3. A stall construction having in combination spaced vertical stanchion frames, a partition member disposed between said frames having a portion extending horizontally, connecting members each having a head portion adapted to partially embrace one of said frames, clamping members adapted to be secured to said head portions for clamping the same on said frames, each of said connecting members also having an offset arm, said arms being adapted to extend towards each other in spaced parallel relation, partition connecting members each having a portion adapted to embrace said partition member, means for connecting said partition connecting members to clamp the same on said partition members, said partition connecting members each having a flange engaging the side of one of said arms and slidable thereon, a means for connecting said flange to said arm and holding the same in various positions thereon, whereby said frames may be secured in various spaced positions.

4. The structure set forth in claim 3, said arm having slots therethrough and said last mentioned means comprising bolts slidable in said slots and passing through apertures in said flanges.

5. A device of the class described having in combination a pair of spaced stanchion frames, a partition member disposed between said frames and extending substantially at right angles thereto, a pair of connecting members having laterally offset arms

extending toward each other, a connecting means adapted to be secured to said partition member disposed between and movable longitudinally of said arms, means connecting said last mentioned means and arms in various positions, said connecting members being reversible and adapted to be attached to either frame, whereby said connecting means may be secured to said arms with said frames quite close together or farther apart.

6. A device of the class described, having in combination, spaced vertical posts, connecting members for said posts, each having a head portion adapted to engage and be secured to one of said posts and having an offset arm projecting from said portion said arms extending toward each other and parallel to a plane passing through the central axes of said posts, said arms being spaced from each other, a horizontally extending bar between said posts, a connecting means extending between said arms and adjustably connected thereto and means securing said connecting means to said horizontal bar.

7. A device of the class described, having in combination, spaced posts, connecting members for said posts, each having a head portion adapted to engage and be secured to one of said posts and having an offset arm projecting from said portion, said arms being adapted to extend towards each other in parallel relation, a horizontally extending bar, a connecting means embracing and secured to said bar and disposed and extending between said arms and adjustably secured thereto.

In testimony whereof I affix my signature.

SAMUEL L. HANSON.
